UNITED STATES PATENT OFFICE.

GEORGE FREDERICK HUMPHREY, OF LONDON, ENGLAND, ASSIGNOR TO ALLIANCE
VEGETABLE COMPANY LIMITED, OF LONDON, ENGLAND.

DEHYDRATING OR DRYING APPARATUS.

1,225,634.

Specification of Letters Patent. Patented May 8, 1917.

Application filed September 20, 1916. Serial No. 121,213.

To all whom it may concern:

Be it known that I, GEORGE FREDERICK HUMPHREY, a subject of the King of Great Britain, residing at 52 New Broad street, 5 London, England, have invented certain new and useful Improvements in Dehydrating or Drying Apparatus, of which the following is a specification.

This invention relates to improvements in apparatus for dehydrating food stuffs such as vegetables, fruit, fish or like purposes, such as the drying of flowers and foliage.

The invention relates more particularly to apparatus in which hot air is passed through chambers containing the materials to be treated.

The objects of the present invention are to facilitate the control of the supply of 20 heat and air, to permit of easy access to any part of the apparatus, and particularly to enable the operation to be continued and without waste during the discharging and recharging of one or more of the chambers.

According to the invention each unit comprises a pair of drying chambers arranged back to back, with heating chambers below and above, suitable means being provided by which air is led either through the heating and drying chambers of each unit in series, or through one heating chamber and either of the drying chambers only, while the other is being recharged.

The invention also comprises the arrangement of common inlet and outlet ducts for a plurality of units or pairs of drying chambers, whereby the air is led to and from the units in parallel.

The invention further comprises details 40 hereinafter referred to.

In the drawings,

Figure 1 is a sectional side elevation of one form of apparatus, and

Fig. 2 is a front elevation corresponding 45 thereto.

Fig. 3 is plan on a smaller scale.

Fig. 4 is a sectional side elevation of another form of apparatus.

In the form of apparatus illustrated in 50 Figs. 1 and 2, wherein one unit is shown, each unit comprises a pair of drying chambers *a*, *b*, arranged back to back. Each drying chamber has a door *c* in front, preferably one adapted to slide vertically between uprights or jambs *d*, and being balanced by

weights *e*, connected to the doors by cables *f*, running over pulleys *f*, as commonly adopted with a certain type of window. The chambers *a*, *b*, are mounted on a brick base *g*, inclosing two ducts, one *h*, an inlet duct, and the other *i*, an outlet duct, running longitudinally of the apparatus. Air is supplied to the inlet duct *h*, by any suitable means, for instance in a large plant comprising a number of units, as indicated somewhat diagrammatically in Fig. 3, a fan *j* is connected to each end of the duct *h*, the duct being divided by a wall *m* in the middle. The outlet duct is similarly divided by a wall *n*, and has a discharge duct *o* leading to the atmosphere.

A heating chamber *p*, separated from the ducts *h* and *i* by walls *q*, *r*, is situated beneath each pair of drying chambers *a*, *b*. One or more openings *s* are provided in the wall *q*. Openings *s*, *t*, controlled by any suitable means, such as sliding dampers *u*, *v*, enable the heating chamber *p*, to be connected to either of the drying chambers *a* or *b*. A second heating chamber *r'* is arranged above the chambers *a* and *b*, and has openings *w*, *x*, controlled by any suitable means such as sliding dampers *y*, *z*. An opening *z* connects the chamber *b*, with the air outlet duct *i*, the opening being controlled by suitable means such as by a sliding damper *z*, enabling either or both of the chambers *a*, *b*, to be put into connection with the chamber *r'*. Directly above the opening *w* is a discharge opening *2*, which 90 discharges through a discharge main or flue 3 to the atmosphere. Means for controlling the opening *2* are provided, such as a damper 4.

The heating chambers *p*, *r'*, are provided with any suitable form of heating device, steam radiators 5 and 6 being indicated, the radiators being connected with a steam supply main 7 by pipes 8 and 9 and with a return main 10 by pipes 11 and 12. Valves 13, 14, for controlling the supply of steam are operated from the outside by handles 15, 16. Trays 17, having perforated, gauze or network bottoms are shown at 7^a in the partially broken away portion as are well known in the art and need no further description, are suitably supported as by angle irons or runners 18, fixed to the side walls 19 of the drying chambers *a* and *b*, the trays being slid into and out of position 110

when the doors *c*, *c* are opened. Movable frames 21, 22, are provided in the chambers *a* and *b*, the frames being for instance pivoted on trunnions 23, 24. In the normal position, namely when both drying chambers *a* and *b*, are in use as hereinafter explained, the frames 21, 22, occupy the positions indicated in Fig. 1, their upper ends resting against stops 25, 28. When either chamber *a* or *b* is being emptied or recharged the frame 21, or 22, of the other chamber is moved about its pivots or trunnions so that it occupies a position with one end resting against stops 27 or 28. In whatever position the frames are set, the trays are set with their adjacent corners in contact therewith. In this way the trays are ranged or set to leave tapering spaces 30, 31, for conducting the air from the respective inlet openings *s*, *t*, or *w*, to the trays, which are spaced apart to allow the air to pass between all the trays to dry the vegetable or other material thereon.

Assuming the trays in both chambers *a*, *b*, to be charged with shredded vegetable or other food stuff to be dried, the frames 21, 22, are set as indicated in Fig. 1, and the dampers *u*, *y*, *z* and 33 are moved to expose the respective openings *s*, *w*, *x* and 32, whereas the dampers *t* and *v* are moved to close their respective openings 2 and *t*. Air then passes as indicated by the various arrows, from the inlet duct *h*, through the opening 34 into the heating chamber *p*, being directed over the radiator 5, by a deflector 35, so that it is heated thereby, and then passes through the opening *s*, into the tapering space 30, and is distributed between and among all the trays 17 and drying the material thereon. The moist air then escapes through the opening *w*, into the heating chamber *v'*, wherein it is directed by a deflector or baffle 36 over the radiator 6, being re-heated thereby so that it is ready to take up more moisture. The reheated air passes through the opening *x* into the tapering space 31 and is distributed between and among the trays 17 in the chamber *b*, drying the material thereon and escaping through the opening 32 into the outlet duct *i*, and thence to the discharge duct *o* to the atmosphere.

The air from the inlet duct *h* thus passes in series through the heating chambers and drying chambers, but is distributed in parallel between the trays 17.

When the chamber *a* is being emptied or recharged, the dampers *u* and *z* are moved to close the openings *s* and *x*, and the frame 22 is moved into the position indicated in dotted lines so that the trays 17 are rearranged to leave a tapering space 31 which is wider at the bottom. This may be simply effected by pushing inwardly the upper trays so that they force the frame 22 against the

stop 28. The hot air from the heating chamber *p* then passes through the opening *t*, directly into the drying chamber *b*, and thence to the duct *i*. If the chamber *b* is to be emptied and recharged then the dampers 70 *v* and 33 are moved to close the openings *t* and 32, and the dampers *u* and *y* and *t* are moved to uncover the openings *s*, *w* and 2, so that the hot air from the chamber *p*, passes through the chamber *a* only, and escapes through the opening 2. It is thus clear that the air may be directed through the heating chambers and drying chambers in series or through one heating chamber and either drying chamber. 80

By arranging a number of chambers *a*, *b*, back to back they are easily accessible, and by also providing the means for altering the course of the air as above described, the chambers may be systematically charged, 85 emptied and recharged without stopping operations.

For maturing fruit it is desirable to pass the air up through the trays in series instead of passing it through or between them 90 in parallel. A modification for this purpose is illustrated in Fig. 4. In this figure similar parts are indicated by reference characters corresponding to Figs. 1 and 2. In this form of the apparatus a valve chest 95 41 is arranged above the heating chamber *p* and is fitted with three valves or dampers 38, 39 and 40. The valve 38 controls the supply of air from the heating chamber *p* to the chest 41. The valve 39 controls the supply of air from the chest 41 to the space 43 below the trays 17 in the chamber *a*, which trays are set up against a partition 44. The valve 40 controls the supply of air from the chest 41 to a by-pass 46 which leads the 100 air to the damper *z* controlling the opening *x* leading to the space 47 above the trays 17 in the chamber *b*, which trays are set up against a fixed partition 45.

When the air is to pass from the inlet duct *h* in series through the heating chamber *p*, drying chamber *a*, heating chamber *v'*, drying chamber *b*, and thence to the outlet duct *i*, the valves or dampers 38, 39, *y*, *z*, and 33 are opened, the others being closed. 115 If the air is to pass only through the chamber *a*, the valves or dampers 38, 39, *y* and *t* are opened the others being closed. If the air is to pass only through the chamber *b*, then the valves 38, 40, *z* and 33 are opened the others being closed. As before stated sliding dampers may be used, such as for instance dampers of the sliding louver type, and any usual means may be employed for operating them but as these are well known in the art no further description need be given. 125

I claim:—

1. Apparatus for dehydrating food stuffs, 130 comprising a pair of drying chambers, ar-

ranged back to back, heating chambers above and below said drying chambers, said heating chambers having heaters therein, and communicating with both of said drying chambers, an air inlet duct communicating with the lower of said heating chambers, air outlet ducts communicating with said drying chambers, and means for opening and closing the communications between the said heating chambers and said drying chambers, whereby air is led either through the heating and drying chambers in series, or through one heating chamber and either of the drying chambers only while the other drying chamber is being recharged.

2. Apparatus for dehydrating food stuffs, comprising a number of units each consisting of a pair of drying chambers arranged back to back, and heating chambers below and above said drying chambers, an air inlet duct common to all of the lower heating chambers, and air outlet ducts common to all of the units, and means for directing the air from said common air inlet duct through the heating chambers and drying chambers of each unit, in series, to one of the common air outlet ducts, and means for changing the course of the air and for directing it through one heating chamber and either of the drying chambers of a unit only when the other drying chamber of said unit is being recharged.

3. Apparatus for dehydrating food stuffs, comprising a number of units, each consisting of a pair of drying chambers arranged back to back, a partition separating said chambers, heating chambers below and above said drying chambers, an air inlet duct common to the units, an outlet duct common to the units, means for controlling the communication between the said ducts, drying chambers and heating chambers, trays within the drying chambers, and means for positioning the trays whereby a tapered air space is left between the aforesaid partition and the adjacent ends of the trays, substantially as and for the purpose hereinbefore set forth.

4. An apparatus for dehydrating food stuffs, comprising a number of units, each having two drying chambers arranged back to back, an air inlet duct, and air outlet ducts, means for heating the air before entering the chambers, means for heating the air at the outlet of one of said chambers, means for connecting said units to said ducts so that the air passes from the said inlet duct in parallel through the units to one of the outlet ducts, and means whereby the heated

air may be directed through but one chamber 60 or directed through the said latter chamber and subsequently heated and passed through the other chamber.

5. Apparatus for dehydrating food stuffs, comprising a number of units each having two drying chambers arranged back to back, and two heating chambers, an air inlet duct, and air outlet ducts, means for connecting said units to said ducts so that the air passes from the said inlet duct in parallel through 70 the units to one of the outlet ducts, and means whereby the air may be directed in each unit either through the two heating chambers and two drying chambers in series, or through one heating chamber and either 75 of the drying chambers, substantially as and for the purpose hereinbefore set forth.

6. Apparatus for dehydrating food stuffs, comprising a number of units each having two drying chambers arranged back to back, 80 and two heating chambers, an air inlet duct, and air outlet ducts, means for connecting said units to said ducts so that the air passes from the said inlet duct in parallel through the units to one of the outlet ducts, and 85 means whereby the air may be directed in each unit either through the two heating chambers and two drying chambers in series, or through one heating chamber and either of the drying chambers, the aforesaid air 90 inlet duct having a central partition, and a fan at each end of said air inlet duct, substantially as and for the purposes hereinbefore set forth.

7. Apparatus for dehydrating food stuffs, 95 comprising a number of units, each consisting of a pair of drying chambers arranged back to back, a heating chamber for each drying chamber, and adjacent thereto, steam radiators in said heating chambers, an air 100 inlet duct, and air outlet ducts, the adjacent walls of the heating chambers and drying chambers having openings for effecting intercommunication therewith, dampers for controlling said openings, means for effecting 105 communication between the air inlet duct and one of said heating chambers of each unit, and means for effecting communication between one of the drying chambers of each unit and the outlet duct, substantially as and 110 for the purpose hereinbefore set forth.

In testimony whereof I have signed my name to this specification in the presence of two subscribing witnesses.

GEORGE FREDERICK HUMPHREY.
